(57) **CLAIM**

The ornamental design for a "snow making machine," as shown and described.

DESCRIPTION

FIG. 1 is a front elevational view of an embodiment of a snow making machine according to the present subject matter;

FIG. 2 is a rear elevational view of the embodiment of the snow making machine shown in FIG. 1 according to the present subject matter;

FIG. 3 is a right side elevational view of the embodiment of the snow making machine shown in FIG. 1 according to the present subject matter;

FIG. 4 is a left side elevational view of the embodiment of the snow making machine shown in FIG. 1 according to the present subject matter;

FIG. 5 is a top plan view of the embodiment of the snow making machine shown in FIG. 1 according to the present subject matter;

FIG. 6 is a bottom plan view of the embodiment of the snow making machine shown in FIG. 1 according to the present subject matter; and,

FIG. 7 is a top perspective view of the embodiment of the snow making machine shown in FIG. 1 according to the present subject matter.
